UNITED STATES PATENT OFFICE.

EINAR WESTERGARD, OF HOLLYOAK, DELAWARE.

GLAZIER-BOX.

1,310,725.

Specification of Letters Patent. Patented July 22, 1919.

Application filed June 14, 1918. Serial No. 240,022.

To all whom it may concern:

Be it known that I, EINAR WESTERGARD, a citizen of the United States, residing at Hollyoak, in the county of New Castle, State 5 of Delaware, have invented certain new and useful Improvements in Glazier-Boxes; and I do hereby declare the following to be a full, clear, and exact description of the invention, such as will enable others skilled in the art 10 to which it appertains to make and use the same.

The invention relates to a hand box, and more particularly to the class of roof glazing boxes.

15 The primary object of the invention is the provision of a box of this character, wherein the same is partitioned to divide it into a number of compartments, the sizes of which are different from each other and are particularly constructed for receiving glazing tools, paint cans, putty, tacks, brads and other paraphernalia ordinarily required and used for glazing purposes, thereby enabling the user to readily procure therefrom the 20 tools and accessories when engaged in glazing a roof or the like, the box being of novel form and is adjustable for its support in proper position for handy access to the user.

Another object of the invention is the provision of a box of this character, wherein the construction thereof permits easy and convenient handling of its contents, and for the convenience of the user in traveling, the box 30 being designed to serve as a general handy box for any practical purpose and can be set level on an incline so as to avoid the upsetting or turning over thereof.

A further object of the invention is the provision of a box of this character, which is 35 extremely simple in construction, convenient, durable, reliable and efficient in its purpose and inexpensive to manufacture.

With these and other objects in view, the invention consists in the features of construction, combination and arrangement of parts 45 as will be hereinafter fully described, illustrated in the accompanying drawing and pointed out in the claim hereunto appended.

In the accompanying drawing:

50 Figure 1, shows an end elevation of a box constructed in accordance with the invention, the same being disposed upon an incline in its level position.

Fig. 2, is a top plan view of the box with 55 the cover broken away.

Fig. 3, is a vertical sectional elevation.

Fig. 4, is a vertical transverse sectional elevation.

Fig. 5, is a fragmentary vertical sectional view taken through one of the legs. 60

Similar reference characters indicate corresponding parts throughout the several views in the drawings.

Referring to the drawing in detail, the box 65 comprises a substantial rectangularly shaped body 10, preferably made from sheet metal although the same may be made from any other suitable material and can be of any desirable shape and dimensions. Slidable through the front of the body of the box 10 70 is a comparatively shallow drawer 11 which is supported on guide cleats 12 adjacent to the bottom of said body and this drawer contains the necessary tools, for example, a hammer, brushes or any other accessories, the 75 same may contain glass.

At the front and rear of the body 10 and extending longitudinally thereof spaced from its side walls, are vertical partitions 13 forming compartments 14, while between 80 these partitions 13 is a nest of partitions 15, forming a series of different sizes of compartments, certain of which contain removable trays 16, while the others are adapted to receive tacks, brads, paint can and glazing 85 tools, one of the latter compartments being formed with an inclined bottom 17, to support the tools at an inclination to assure easy accessibility and view thereof when contained in the box. Hinged to the rear wall of 90 the body 10, is a swinging lid or cover 18, while bridging the front longitudinal compartment 14 centrally thereof is a bridge plate 19 supporting a hasp eye 20, the cover or lid 18 being formed with a slot 21 for said 95 hasp eye 20 to permit the fastening of the lid or cover closed.

On the front of the drawer 11 is a multiple hinged leaf hasp 22, the slotted leaf 23 of which is adapted to engage the hasp eye 20 100 so this drawer can be fastened closed.

Secured to opposite ends of the body 10, are handle bearings 24 to which is pivoted a bail handle 25 carrying a hasp 26 and engaging the hasp eye 20 when the handle is 105 in lowered position for the fastening thereof. The cover or lid 18 is removably connected to the rear wall of the body 10 of the box and is adapted when closed to telescope over the open top of the body. 110

Detachably and adjustably mounted at the opposite ends of the body 10 are supporting

legs 27, which are longitudinally slotted at 28 to receive bolts 29, removably fitted in the ends of the body 10 and carrying winged clamping nuts 30 so that the legs 27 can be 5 adjustably fastened to said ends of the body and vertically adjusted to bring the box to a level when resting upon an inclined base or roof, the legs 27 when removed being placed within the body of the box and likewise the 10 bolts 29 are disengaged and placed within said box.

From the foregoing it is thought that the construction and manner of the use of the box will be clearly understood and therefore 15 a more extended explanation has been omitted.

What is claimed is:

A box of the character described, comprising a body having a slideable drawer in its 20 lower portion, a plurality of partitions ar-

ranged in the body and forming independent compartments therein, trays removably held in certain compartments, a cover removably fitted on the body and having a hasp eye receiving the opening, a hasp eye support in 25 bridging relation over one of the compartments and received in the opening in the cover, a hasp on the drawer and engageable with the hasp eye, a bail handle swingingly connected to the body and having a hasp engageable with said hasp eye, and detachable and adjustable legs mounted on opposite ends of the body for supporting the latter level when resting on an incline.

In testimony whereof, I affix my signature, 30 in the presence of two witnesses.

EINAR WESTERGARD.
